US00D960559S

(12) **United States Design Patent** (10) **Patent No.:** **US D960,559 S**
(45) **Date of Patent:** **** Aug. 16, 2022**

(54) **BAG**

(71) Applicant: **Inhyuck Lee**, Seoul (KR)

(72) Inventor: **Inhyuck Lee**, Seoul (KR)

(**) Term: **15 Years**

(21) Appl. No.: **29/760,047**

(22) Filed: **Nov. 27, 2020**

(30) **Foreign Application Priority Data**

May 29, 2020 (KR) 30-2020-0023856

(51) **LOC (13) Cl.** **03-01**

(52) **U.S. Cl.**

USPC **D3/216**

(58) **Field of Classification Search**
